UNITED STATES PATENT OFFICE.

HERMAN E. JAECKEL AND GUSTAVE O. MATTER, OF PORTLAND, OREGON; SAID
MATTER ASSIGNOR TO SAID JAECKEL.

TILE-MAKING MACHINE.

1,146,168.

Specification of Letters Patent. Patented July 13, 1915.

Application filed May 27, 1911. Serial No. 629,956.

To all whom it may concern:

Be it known that we, HERMAN E. JAECKEL and GUSTAVE O. MATTER, citizens of the United States, residing in the city of Portland, county of Multnomah, and State of Oregon, have invented certain new and useful Improvements in Tile-Making Machines, of which the following is a specification.

Our invention relates to tile making machines, and more particularly to certain improvements in machinery for making tile, pipe sections, and the like, of plastic material, whereby an improved glazed article is secured in a more practical and economical manner.

Among the salient objects of our invention are,—to provide in a machine of the character referred to, a construction wherein the core remains stationary and the outer casing or form is revolved around it, while concrete or other plastic material is being fed and tamped into the space between said core and form, said material being so supported as to revolve with the form or outer casing around the core, thereby giving a smooth, glazed surface to the inside of the material, as it is formed into a tile or other cylindrical object; to provide in a machine of the character referred to, an improved core and form or outer casing, whereby it is possible to hold the core stationary, or to raise and lower it at will, and to revolve the form or outer casing around the core during the formation of the tile therein; to provide a suitable support for said form or casing with means for revolving same and upon which said form or casing can be detachably mounted to receive the tile and from which it can be readily removed with the tile, when the latter is completed; to provide in a machine of the character referred to, improved means for feeding and tamping the material into the form as it is revolved around the core; and, in general, to provide an improved tile making machine by means of which it is possible to quickly and economically form a tile pipe, or other cylindrical object and to remove same without injury thereto.

Other advantages and important features will appear from the following description, taken with the accompanying drawings illustrating one practical embodiment of the invention, and in which drawings,—

Figure 1 represents a front elevation of one embodiment of the invention, with parts

broken away to show the construction; Fig. 2 is a side elevation of the same; Fig. 3 is a side elevation of a tile with the core partially removed and the form or outer casing wholly removed therefrom; Fig. 4 is a top plan view of the form or outer casing without the head or bell portion; Fig. 5 is a vertical sectional view thereof, taken on line 5—5 of Fig. 4; Fig. 6 is a top plan view of the core; and Fig. 7 is a vertical sectional view taken on line 7—7 of Fig. 6.

Referring now to the drawings, especially Figs. 1 and 2, a suitable foundation is prepared of concrete or masonry, said foundation preferably comprising a walled excavation as 1, in which is fixed a supporting bar or I-beam 2, the ends of which are preferably secured in the wall of said foundation, as indicated. We preferably provide two turn-tables 3—3 rotatably mounted in suitable bearings 4—4 in the I-beam 2, said turn-tables having mounted upon the lower ends of their main shafts, beveled gears 5—5, which beveled gears mesh with other beveled gears 6—6, mounted upon a shaft 7, supported in suitable bearings 8—8 and driven from a sprocket wheel 9 over which runs a sprocket chain 10, driven from a small sprocket wheel upon a driving shaft 11. Two clutch members 12—13 are mounted upon the shaft 7 so as to turn therewith and are adapted to be operated by means of a lever 14 whereby one or the other of said clutch members can be drawn into operating connections with the beveled gears 6—6, which turn loosely upon the shaft 7 until one of the clutches 12 or 13 is moved into connection therewith by means of the lever 14. Through this mechanism, one or the other of said turn-tables 3—3 is operated, said turn-tables are preferably on a floor or ground level, as indicated.

The turn tables 3—3 are each provided with a series of holding hooks 15, adapted to hook over base pieces 16 on the bottom of the form 17, when placed upon said turn-table, said hooks and base pieces co-operating to hold the forms 17 so that they will revolve with the turn-tables 3—3. The construction of these forms 17 is clearly shown in Figs. 3, 4, and 5. The forms are preferably constructed in two halves so as to be removed from the formed tile in the manner indicated in Fig. 3. The top or bell portion 18 of the form may be of cast iron, as may

also be the base ring 19, while the middle portion 20 thereof, is preferably sheet metal and can be replaced when worn. The top or bell portion 18 is preferably provided 5 with lifting pins as 21, while the base ring 19 is provided with an inner ring as 22, having a beveled edge as at 23 whereby it is supported upon the inturned beveled edge of the base ring 19. The two parts of the 10 form are clamped together by means of a clamping yoke 24, hinged upon one-half of the form and adapted to be turned over an angle clamping plate 25, upon the other half of said form, with the link portions of said 15 yoke resting in notches 26 in said clamping plate 25. Guide clips 27-27 at the meeting edges of said form coöperate in bringing and holding the two parts of the form in proper relationship. A clamping means is, 20 of course, provided at each side of the form.

A suitable frame work preferably constructed of I-beams and channel iron is erected over the turn-tables for the purpose of supporting the mechanism for lifting the 25 cores and for holding the feeding and tamping mechanism.

The cores 28, shown in Figs. 6 and 7, are each adapted to be supported at the end of a rod 29, preferably screwed into the core, 30 said rod carrying at its opposite end, a piston head working in a cylinder 30. It is intended that this cylinder 30 be connected with any suitable source of air or liquid under pressure, for the purpose of raising or 35 lowering the piston rod 29, and the core 28 carried thereby. The core 28, like the form 17, is preferably constructed with a cast iron head 31, with strengthening ribs or webs, as indicated in dotted lines Fig. 6, and a cast 40 iron base piece 32, provided with a central opening 33, adapted to rest upon a center pin 34 on the turn-table. The middle portion of said core is preferably made of sheet metal and can be replaced when worn. The 45 head piece 31 is provided through one side of the flange thereof with an opening 31' for a purpose hereinafter more particularly referred to. Said head is also provided with a vent opening 35, for the admission of air 50 which passes into said core and through openings 36 as the core is being raised from the formed tile, also hereinafter again referred to.

37 designates a hopper to receive the material of which the tile is to be formed, said hopper discharging into a pipe 38, pivotally supported at 39, so that it can be swung from one side of the machine to the other at will. The pipe 38 is provided with a dis- 55 charging joint 40, preferably having a reduced end adapted to discharge the material into the space between the form and the core, as clearly indicated in Fig. 1. The dis- 60 charging section of the pipe 39 has tele- 65 scopic engagement with the other sections of

the pipe and carries a rod 41 working through a holding mechanism 42 and by means of which the position of said discharging pipe can be regulated. Mounted to revolve within the hopper 37 is a stirring 70 mechanism 43 adapted to agitate the material therein and cause it to feed more readily into the pipe 38. This stirring mechanism is operated through a pair of beveled gears at 44 which are operated through a sprocket 75 chain 45, from a sprocket wheel upon the shaft 46. Said shaft 46 is operated through a pulley at 47 by means of a belt 48 running to the pulley 49, which latter pulley is driven by means of a belt 50, running upon a pulley 51, upon a driving shaft at 11, shown in Fig. 2.

Mounted to travel upon racks 52, Figs. 1 and 2, is a tamping mechanism 53, said tamping mechanism comprising a carrier 80 frame with the gears 54 meshing with said racks, and mounted upon a short shaft which is operated by means of a sprocket chain 55, which is in turn operated from a hand wheel 56 for the purpose of carrying the tamping 85 mechanism from one side of the machine to the other upon said racks. Supporting rods 53', support a reciprocating holding frame 57, which moves upon said rods and is operated by means of a rod 58 driven by an 90 eccentric 59, upon a shaft 60, which said shaft is driven through a sprocket chain 61, from a sprocket wheel 62 upon the end of the shaft 46. Tamping strips or rods 63-63, preferably flat and adjustably mounted in 95 the holding frame 57, are yieldingly held in place by means of leaf springs arranged to be pressed against said tamping strips by means of eccentric cams at 64, said cam being mounted between the plates of the frame 100 57 and operable by means of small hand levers 65. There are two tamping strips or rods mounted in the frame 57 so that either one or the other can be used, depending upon which turn-table is in use. It will be noticed 105 in Fig. 1 that the tamping rod is projected through the opening 31' in the flange of the core 28, and extends down into the space between said core and the form or outer casting 17, there being sufficient space to permit a free reciprocating movement of said 110 tamping strip or rod for the purpose of tamping the material into the form. When the form has been filled up to the flange on the core, the tamping mechanism is shifted 115 slightly, so that the tamping strip or rod 63 will work within the bell of the form, and outside of the flange upon the core, thus tamping the material into the bell portion 120 of the form.

In order to shift the tamping mechanism, it is only necessary to turn the little hand wheel 56 which operates the gears 54, which are in mesh with the rack 52, and the whole 125 tamping mechanism, and the pipe 38, are 130

5 moved from one side of the machine to the other. The driving eccentric 59 of said tamping mechanism, slides upon the shaft 60, being attached thereto by means of a spline and feather so as to turn therewith.

10 A clutch member 66 upon the shaft 46, is operated by means of a handle 67 and used to throw the stirring and tamping mechanisms into and out of operation, said clutch member 66 being secured to turn with said shaft, and at the same time to slide thereupon, while the pulley 47 runs loosely upon said shaft.

15 In order to prevent the core from turning as the form revolves around it, we attach thereto, an arm 68 adapted to have sliding engagement with a guide rod 69, and having an anti-friction roller 70 so that the arm 68 will not interfere with the 20 free vertical movement of the core when it is lifted out of the form 17.

25 The operation of the device may be briefly described as follows: Assuming the parts to be in the positions shown in Figs. 1 and 2, and that power is being applied to the driving shaft 11, the pulley 49 is operated through the belt 50, and the shaft 46 is operated through the belt 48; the clutch mechanism 66 has been thrown into engagement 30 with the pulley at 47 so that the shaft 46 is revolving. The stirring mechanism in the hopper 37 is being operated through the sprocket chain 45 and the material is being fed through the pipe 38 into the space between the form or outer casing 17, and the core 28. The turn-table upon which said form is mounted is being driven through the sprocket chain 10, so that the form with the ring 22 (Fig. 5) is turning around the 35 core 48. Through the sprocket chain 61, the shaft 60 is operated, which in turn operates the eccentric drive 59 and reciprocates the tamping head or frame 57. The tamping rod 63 is working through the opening 31' 40 in the stationary core 28, tamping the material into the space between the core and the outer casing, as said outer casing, together with the material, is being revolved around said core. The movement of the 45 outer casing with its ring 22, carries the material in rubbing engagement around the core, thereby giving a smooth and glazed finish upon the inside of the tile or pipe being formed. When the material reaches 50 the flange upon the core, the tamping mechanism is slightly shifted so as to bring the tamping rod 63 just outside of the opening 31', thereby tamping the material into the bell portion of the form, as the form and the 55 material revolve around the core. When the form is filled, the tamping mechanism is moved to the other side of the machine by turning the little hand wheel 56, which operates the gears at 54, and carries the 60 tamping mechanism upon the racks 52, to

the other turn-table and the core lowered thereinto, ready to receive the material which is tamped into the form by the tamping rod at the other side of the tamping frame 57. Air under pressure is now admitted to the cylinder 30, which operates to lift the piston therein and thereby lifts the core 28 from the form which has just been filled. The form with the tile therein is now carried from the turn-table and placed upon a suitable platform, or other support, the clamping mechanism 24 is released, and the two-halves of the form are drawn away from the tile formed therein, in the manner indicated in Fig. 3, leaving the tile resting upon the ring 22.

10 While we have here shown and described one practical embodiment of our invention, we are aware that modifications and changes can be made therein without departing from the spirit of the invention, and we do not, therefore, intend to limit ourselves to the particular showing here made for the purpose of illustration.

15 We claim:

1. In combination with a tile form having a head or bell portion, a core member having a flange portion and adapted to fit within said form with space therebetween, said flange portion having a tamping opening therethrough in alinement with the space between said form and core.

2. In combination with a turn table and means for turning same, a tile form having a head or bell portion, and detachably mounted upon said turn table, a core member having a flange portion and fitted within said form with an annular space therebetween, said flange portion having an opening therethrough in alinement with the space between said form and core for tamping purposes, and means for removing said core from said form.

3. In a tile making machine, a turn-table and means for turning same, a sectional form detachably mounted upon said turn-table to turn therewith, a core with flange portion having an opening therethrough, a removably supporting ring in said form to support the material and to carry it with the form around said core, a reciprocating tamping member working through the opening in said core flange in the space between said core and said form and means for operating same, and a supply pipe discharging into the space between said core and said form or outer casing as the latter revolves around the core.

4. In a tile making machine, a turn-table and means for turning same, a sectional form and means for detachably holding same upon said turn-table to turn therewith, a core and means for holding same stationary within said form, means for lifting said core vertically from said form, said

- form being provided with a head or bell portion, said core being provided with a flange portion with an opening therethrough in alinement with the space between the body portions of said form and said core, a tamping member adapted to operate through the opening in the flange of said core and in the space between said core and said form, said tamping member being adapted to be shifted so as to operate in the bell portion of said form outside of said flange, and means for operating said tamping member.
5. In a tile forming machine, a sectional form with a supporting ring held in the bottom thereof when the parts of said form are assembled, said form being provided with a bell portion at its top, a core within said form and having a flange adapted to rest within the bell portion of said form, said flange having an opening therethrough in alinement with the space between the body portions of said core and said form, means for holding said core stationary, means for supporting and revolving said form around said core, a reciprocating tamping member working through the opening in said flange and in the space between said form and said core and means for operating same, and means for lifting the core bodily from said form.
6. In a tile making machine, a pair of turn-tables and means for operating same, sectional forms adapted to be detachably mounted upon said turntables, a pair of cores mounted one above each turn-table and adapted to be lowered into and lifted from the forms placed upon said turn-tables, means for raising and lowering said cores at will, a supply hopper for receiving the material of which said tiles are to be formed, a feed pipe from said hopper, pivotally mounted so as to be moved from one position to another, and a tamping member movably supported upon a fixed support so as to be shifted from one turn-table to the other and means for shifting same, whereby said tamping member can be operated in one form or the other, and means for operating said tamping member.
7. In a tile making machine, the combination with turn-tables, cores, tamping members and means for operating same, of a feed hopper adapted to receive the material, a stirring mechanism within said hopper and means for operating same, a feed pipe from said hopper, pivotally mounted so that the lower end thereof can be moved from one form to another at will, said feed pipe being connected with the tamping member and movable therewith when the latter is shifted from one form to the other.
8. In a tile making machine, the combination with the forms, cores, and feeding mechanism, of a tamping mechanism comprising a driving shaft and driving con-

nections therefor, an eccentric slidably mounted upon said shaft and adapted to be operated thereby at any position thereupon, a tamping frame or head operatively connected with said eccentric and adapted to be reciprocated thereby, and means for shifting said tamping mechanism upon said driving shaft from one form to another for the purpose indicated.

9. In a tile making machine, the combination with forms, cores, and feeding mechanism thereof, of a tamping mechanism comprising a rack, a driving shaft with driving connections therefor, a tamping frame, supported upon said rack and said shaft and movable thereupon from one position to another, an eccentric mounted upon said shaft and operated thereby, said eccentric being movable thereupon with said tamping frame, a tamping strip carried by said tamping mechanism and adjustable therein during the tamping operation, means yieldingly holding said tamping strips in operative position, and means for moving said tamping mechanism upon said rack and driving shaft from one form to another.

10. In a tile making machine, a sectional tile form comprising cast-iron bell and base ring portions with sheet metal body, said base ring portion having an inwardly projecting beveled bottom edge, a ring member having a beveled outer edge and adapted to rest flush upon the inturned beveled edge of said base ring, and means for clamping the tile form sections together with the ring wholly within the tile form, substantially as shown and described.

11. In combination with a tile making machine of the character referred to, a sectional form, a core adapted to be supported within said form, said form and said core being provided respectively, with cast-iron bell and flange portions, the flange of said core being provided with a tamping opening therethrough in alinement with the space between said core and form, said form and said core having sheet metal body portions adapted to be replaced when worn, said form being composed of two sections, and means for locking said sections together.

12. In a tile making machine of the character referred to, the combination with a turn-table and means for driving same, a tamping member and means for operating same, and a core lifting device and means for operating same, of a sectional form adapted to be detachably mounted upon said turn-table to turn therewith and having a removable supporting ring in the bottom thereof to support the tile to be formed therein, said form having cast-iron bell portion and base ring and a sheet metal body portion, and a core having sheet metal body portion with a cast-iron flange portion, said flange portion arranged to rest within the

bell portion of said form and having a tamping opening therethrough in alinement with the space between the body portions of said form and said core, and means holding said core stationary during the revolving of said form thereabout, substantially as described.

Signed at Portland, Oregon, this 17th day of May, 1911.

HERMAN E. JAECKEL.
GUSTAVE O. MATTER.
